UNITED STATES PATENT OFFICE.

OSCAR E. ZENKER, OF BROOKLYN, NEW YORK, ASSIGNOR TO RELIANCE FIREPROOF DOOR CO., OF BROOKLYN, NEW YORK, A CORPORATION OF NEW YORK.

METAL DOOR AND THE LIKE.

Application filed October 5, 1925. Serial No. 60,429.

My present invention relates to metal doors, windows and the like, and aims to devise structures of the general character specified above, which are simple in construction, 5 easy and convenient to fabricate and to assemble, economical in the amount of labor and material required for their assembling, and which are neat and attractive in appearance and rugged in construction. Other objects and advantages of the present invention will in part be pointed out in detail subsequently in this specification and will in part be obvious to those skilled in the art to which the present invention relates.

15 In the accompanying specification I shall describe, and in the annexed drawing illustrate, several illustrative embodiments of the articles of the present invention. It is, however, to be clearly understood that my invention is not limited to the specific embodiments thereof herein shown and described for purposes of illustration only.

20 Referring now to the drawing illustrating the aforesaid illustrative embodiments of the present invention:

Fig. 1 is a front elevation, partly broken away, showing a door panel for embodiment in one of the aforesaid illustrative embodiments of the present invention;

25 Fig. 2 is a front elevation in enlarged detail, broken away, showing one of the slots in the panel illustrated in Fig. 1 of the drawing;

Fig. 3 is a cross-sectional view taken along line 3—3 of Fig. 2 of the drawing showing the panel portion illustrated in Fig. 2 of the drawing;

30 Fig. 4 is a view similar to Fig. 3 showing the initial position of one of the welding lugs preferably employed in the first of the aforesaid illustrative embodiments of the present invention;

Fig. 5 is a view similar to Fig. 3 showing the welding lug of Fig. 4 of the drawing in its final position within the slot in the panel in accordance with the aforesaid illustrative embodiment of the present invention;

35 Fig. 6 is a cross-sectional detailed view showing a portion of the completely assembled door made in accordance with the aforesaid illustrative embodiment of the present invention;

40 Fig. 7 is a perspective view of a lug which may be used in fabricating the aforesaid

illustrative embodiment of the present invention;

Fig. 8 is a perspective view of a modified form of lug which may be used in fabricating another of the aforesaid illustrative embodiments of the present invention; and

Fig. 9 is a perspective view of still another form of lug which may be used in fabricating the third and last of the aforesaid illustrative embodiments of the present invention.

Referring now to the aforesaid illustrative embodiments of the present invention, and more particularly to the first of the aforesaid illustrative embodiments of the present invention, as illustrated in Figs. 1 to 7, inclusive, of the drawing, 10 indicates in general a metal door panel preferably of the hollow metal door panel type of construction. For this purpose the metal door panel 10 preferably comprises a substantially flat sheet metal base member 11 having the marginal portion 12 and the cooperating formed sheet metal member 13 having the bevelled portion 14 and the marginal portion 15.

The marginal portions 12 and 15 of the sheet metal members 11 and 13, respectively, thus cooperate to provide the flange portion 16 and the hollow portion 17 which may, if desired, be filled with any suitable filler, such as cork, asbestos or the like. Or, if desired, this filler may consist of beaver board or of a wooden board, this latter arrangement being preferable since the entire panel is to be slotted in the manner shortly to be described. At this stage the sheet metal members 11 and 13 of the door panel 10 may be suitably attached to each other, preferably at the marginal portions 12 and 15 of the same as by spot welding along a series of spaced points, as indicated by reference character 18.

The metal door panel member thus obtained is now preferably provided with a series of spaced slots or other perforations. In the illustrative form of the present invention now being described, the perforations are in the form of a series of slots 20, fourteen such slots being shown in the panel illustrated in Fig. 1 of the drawing. As shown in Fig. 1 of the drawing, the slots 20 are substantially rectangular in configuration and are disposed within the bevelled member 14 with their longer dimensions substantially normal to the edges of the panel adjacent to which the slots are located. Also, as shown in Fig.

1 of the drawing there are three such slots adjacent both the top and the bottom of the door panel 10 and four such slots adjacent each of the lateral edges of the door panel.

5 I now insert into the slots 20 a series of welding lugs generally designated by reference character 30 and comprising in the case of the present illustrative embodiment of the invention now being described the 10 head portions 31 and 32 and the connecting shank portion 33, all as more clearly shown in Fig. 7 of the drawing. The head portions 31 and 32 of the lugs 30 are rectangular and of a size to enable them to be passed into the 15 slots 20 when the lugs 30 are positioned with respect to their respective slots 20 as shown in Fig. 4 of the drawing.

It will therefore be noted that the end portions 31 and 32 constituting the heads of the 20 lugs 30 each have a transverse dimension, in this case the longer dimension of the rectangular heads or end portions 31 and 32, greater than the transverse dimension, in this case the shorter dimension, of the 25 rectangular opening of the respective slots 20. The shank portion 33, on the other hand, is cut away at the sides 34 and 35 of the lug 30 so as to permit the lug 30, when once positioned within its respective slot or perforation 30, to be turned into the final position from the initial position shown in Fig. 4 of the drawing into such final position as shown in Fig. 5 of the drawing. In this position of the lugs, in this case fourteen in number, 35 within the respective slots or other perforations 20, the lugs are suitably positioned on the panel 10 within such perforations for the further steps now to be described.

I now provide one or more auxiliary door 40 members, preferably trim members, and preferably a plurality of such trim members, one for each side of the panel of the door in which the panel is to be incorporated. For this purpose I prefer to employ a plurality of trim 45 members having the profile or cross section shown in Fig. 6 of the drawing. As shown in Fig. 6 of the drawing the trim members, of which a plurality are there shown, each being designated by reference character 40, each 50 comprise the main web portion 41, the longitudinally disposed flange portion 42, the transverse flange portion 43, and the channelled portion 44 provided on its interior with the channel 45. The trim members 40 may 55 be continuously or otherwise formed in a rolling operation from a strip or sheet of metal and may have any desired profile or cross section. I prefer, however, that such trim members shall be provided with the 60 channelled portion 44 and the channel 45, or their equivalents, for a purpose subsequently to be described in considerable detail herein.

Associated with the panel member 10 and the trim members 40 are a plurality of surrounding stile members, here designated by 65

reference character 50. The stile members 50 are of the usual construction and may, for example, be of the hollow metal type of construction, being provided with a filler 51 of cork, asbestos, wood, beaver board, or the like. The stile members 50 may be arranged as desired to constitute either a frame for the panel or may also intersect or pass over the panel, which may itself be divided into several panel portions, as desired. Since this arrangement forms no part of the present invention, it is not deemed necessary to be described here in detail.

In assembling the door, the various members of which have been described in detail above, I insert the lugs 30, which may be termed welding lugs and which may be made of iron or steel, preferably the latter, into the perforations 20 in the door panel member 10 in the manner diagrammatically illustrated in Figs. 4 and 5 of the drawing. The lugs 30 being thus properly positioned within and retained by the perforations 20, or even before the lugs 30 have been so inserted and positioned, I apply the door panel member 10 to the stile members 50, which latter are preferably provided with a plurality of cooperating flange portions 52 and 53. The cooperating flange portions 52 and 53 preferably comprise extensions of the metal sheet or covering of which the hollow metal stile members 50 are preferably formed. The flange portions 52, made up of the marginal members 12 and 15 of the sheet metal portions 11 and 13, respectively, of the metal door panel member 10, are now suitably attached to the flange portions 52 and 53 of the hollow metal stile members 50. For this purpose I may spot weld or otherwise autogenously weld the various flange members just enumerated, along a series of spaced points, as designated by reference character 54 indicating one of such points.

The door panel member 10, thus having been fixed along and assembled with the stile members 50, is now in position to have the trim members 40 or their equivalents applied thereto. For this purpose I apply the trim members 40 to the assembled panel and stile members so that the protruding heads 31 and 32 of the lugs 30, now positioned within the respective slots 20, are received within the channels 45 of the channel members 44 of the respective trim members 40. In this position of the described parts the longitudinal flange 42 of each trim member 40 will be flush with and lie over a lateral portion of the corresponding stile member 50, while the transverse flange 43 will abut against the door panel member 10.

I now suitably attach the trim members 40, or their equivalents, to the door panel member 10 or its equivalent, preferably by means of the welding lugs 30. For this purpose I prefer to spot weld or otherwise autogenously

enously weld the trim members 40 to the protruding ends of the heads 31 and 32 of the respective welding lugs 30. This may readily be done in a manner which will readily be apparent to those skilled in the art to which the present invention relates.

This completes the assembling of the door described above and constituting the first of the aforesaid illustrative embodiments of the 10 present invention. The advantages of the structures embodying the principles of the present invention are numerous and of great practical importance. The devices made in accordance with the principles of the present 15 invention are simple in construction, requiring simple apparatus and few manipulations for their fabrication. These constructions also permit considerable economies in labor, material and power required for their 20 fabrication. The structures are further characterized by their neatness and attractiveness in appearance and their ruggedness and long and satisfactory life. It may here be stated that the method of forming the herein 25 described illustrative embodiments of the present invention forms no part of the present invention and is fully described and illustrated in a copending application of mine filed of even date herewith and entitled 30 "Methods of applying metal trims to doors and the like".

In Fig. 8 of the drawing I have shown in perspective view a modified form of lug which may be embodied in another illustrative embodiment of the article of the present 35 invention. This lug has been generally indicated by reference character 30' and includes the substantially rectangular head or end portion 31' and a lower end portion 32' 40 which is not provided with a head. Accordingly the shank portion 33' of this modified form of lug 30' may be inserted directly into the apertures in the panel member 10 which apertures may be square instead of rectangular. Otherwise the use of the iron or steel, 45 preferably steel, lugs 30' is the same as in the case of the lugs 30 previously described, the ends 31' and 32' of the modified form of lugs 30' entering into the channels 45 of the channel portions 44 of the trim members 40, as 50 in the case of the lugs 30 previously described. The form of the invention utilizing this modified form of lug 30' is otherwise substantially the same and possesses the same advantages as in the case of the embodiment of 55 the invention utilizing the lugs 30 previously described.

In Fig. 9 of the drawing I have illustrated in perspective still another modified form of

lug generally designated by reference character 30'' and comprising the head 31'' and the lower end portion 32'' with the rounded shank portion 33''. It will be noted that the lug 30'' and the portions 31'', 32'' and 33'' of the same are all substantially circular in cross 60 section, for which reason the perforations in the panel member 20 may likewise be circular rather than rectangular or square, as in the case of the two previous modifications of the present invention. The form of the invention utilizing this modified form of lug 30'' is otherwise substantially the same and possesses the same advantages as in the case of the embodiment of the invention utilizing the lugs 30 as already described. 65

What I claim as my invention is:

1. A metal door comprising a metal panel member, surrounding metal stile members, means comprising welded cooperating flange members on said metal panel and surrounding metal stile members for attaching said metal panel member to said surrounding metal stile members, a plurality of metal lugs positioned within perforations in said metal panel member, and a plurality of opposed, 80 cooperating metal trim members, one on each side of said metal panel member, attached to said metal lugs.

2. A metal door comprising a metal panel member, surrounding metal stile members, means for attaching said metal panel member to said surrounding metal stile members, a plurality of metal lugs positioned within perforations in said metal panel member, and a plurality of opposed, cooperating, channelled 90 metal trim members, one on each side of said metal panel member and containing end portions of said metal lugs within their respective channels, attached to said metal lugs. 95

3. A metal door comprising a metal panel member, surrounding metal stile members, means comprising welded cooperating flange members on said metal panel and surrounding metal stile members for attaching said metal panel member to said surrounding metal stile members, a plurality of metal lugs positioned within perforations in said metal panel member, and a plurality of opposed, cooperating, channelled metal trim members, one on each side of said metal panel member 100 and containing end portions of said metal lugs within their respective channels, autogenously welded to said metal lugs. 105

In testimony whereof, I have signed my name to this specification this 24th day of 115 September, 1925.

OSCAR E. ZENKER.
